(57) **CLAIM**

The ornamental design for pavement milling machine as shown and described.

DESCRIPTION

1. Pavement milling machine

1.1 : Front

1.2 : Back

1.3 : Left

1.4 : Right

1.5 : Top

1.6 : Perspective

FIG. 1 is a front view of pavement milling machine; FIG. 2 is a back view thereof; FIG. 3 is a left view thereof; FIG. 4 is a right view thereof; FIG. 5 is a top view thereof; FIG. 6 is a perspective view thereof; Bottom view is omitted because it is rare to be seen; the main design points of this design is the combination of shapes, patterns and colours; use of this design product is for pavement milling.
